UNITED STATES PATENT OFFICE.

JOHN S. PATTERSON, OF EAST NORTHPORT, NEW YORK.

LAUNDRY-CHECKING DEVICE.

Application filed August 20, 1927. Serial No. 214,244.

This invention relates to laundry checking devices whereby a plurality of items belonging to one group may be properly assembled in a designated compartment. The device 5 comprises, broadly, a cabinet having a plurality of open compartments, in which are removably placed open cartons. The front wall of each carton is provided with a removable key-rack of novel construction, upon 10 which keys having the identical conformation of the slots in the rack are adapted to be impaled.

In the accompanying drawings there is illustrated the preferred embodiment of my 15 invention.

Fig. 1 is a perspective view of my improved assembling cabinet and the key-rack in operative position;

Fig. 2 is a perspective view of the rack; 20 Fig. 3 is a front view of the key, and

Fig. 4 is a cross-sectional view of the key-rack and keyway, showing the total impalement of the key on the hook.

Inasmuch as the purposes and uses of this 25 character of checking device, of which this invention forms the mechanical embodiment, are well understood, especially in the laundry industry, a detailed description of its function, except in so far as the application and 30 cooperation of the elements, is concerned, is not thought to be necessary.

The cabinet 1, comprises a plurality of open compartments 2, into which are removably inserted cartons 3, adapted to receive the various articles. The bottom of each compartment is provided with a slidable extension 4 upon which items of apparel 5, may be assembled and the carton supported. The extension of the upper tier of compartments is 40 preferably hinged at 6 so as to permit access to the lower compartments.

A key-rack 7, provided with a lip 8, is adapted to be mounted on the front of the carton and removed when not in use. The 45 rack preferably comprises a plurality of key-ways 9, and which may conveniently be stamped out of one sheet of metal as shown. Each key-way comprises an offset flange 12 along the edge of which is punched out a 50 number of predetermined patterns of similar configuration to conform with the outline of a key 10 adapted to be inserted therein and to be impaled upon a hook 11 secured to the flange medially of each slot.

55 The hook is so arranged with respect to the

slot that unless the key fits the slot, there is only partial impalement, and the key extends out at an inclination. This is notice to the operator that the items to which the keys has been attached are being distributed to the 60 wrong compartment and he will proceed to make the correction.

The key 10 and the rack 7 are provided with identifying characters, such as a numeral so that the same may be readily correlated. But 65 it so happens that occasionally the numerals are misread, and the articles wrongly distributed. It is for the avoidance of such an eventuality that the key system is provided.

The key 10 comprises a safety pin to which 70 is attached a plate bearing an identifying numeral or character and having its periphery notched to conform to the punched-out pattern in the key-way. A hole 13 is punched in the plate so that the key may be impaled 75 on the hook as already described.

I do not limit myself to the particular form of apparatus illustrated and described herein, since the invention is susceptible of other embodiments or modifications which come 80 within the scope of the invention, as defined by my claims.

Having described my invention, what I claim is:

1. A key-rack made of one piece of metal 85 having an attaching flange, a plurality of offset flanges suitably punched along their edges to conform in outline to the periphery of a notched checking pin, and hooks attached to said rack and disposed medially of said 90 punched areas.

2. In combination, a rack member including a plate having a slot extending from one edge and provided with a selectively shaped periphery, a hook carried by the plate and 95 projecting through the slot, and a key member having a head provided with a selectively shaped periphery corresponding to said slot.

3. In combination, a rack member including a body portion and a selector plate portion supported from the body parallel to the body, said plate portion having a slot extending from one edge and provided with a selectively shaped periphery, a hook carried by the plate and projecting through the slot, and a 100 key member having a head provided with a selectively shaped periphery corresponding to said slot.

In testimony whereof I affix my signature,
JOHN S. PATTERSON.
